UNITED STATES PATENT OFFICE.

ALMERON M. LANE, OF MERIDEN, CONNECTICUT.

ALARM-CLOCK.

SPECIFICATION forming part of Letters Patent No. 431,595, dated July 8, 1890.

Application filed March 18, 1890. Serial No. 344,313. (No model.)

To all whom it may concern:

Be it known that I, ALMERON M. LANE, a citizen of the United States, residing at Meriden, in the county of New Haven and State 5 of Connecticut, have invented certain new and useful Improvements in a Combined Clock and Bell, of which the following is a specification.

My invention relates to improvements in a 10 combined clock and bell, and the main objects of my improvement are to simplify the construction, to produce the article at a small cost, to arrange the same for convenience in assembling the parts, and to adapt the bell to 15 a central winding mechanism.

In the accompanying drawings, Figure 1 is a front elevation of my combined clock and bell, and Fig. 2 is a vertical section of a portion thereof on the line α α of Fig. 1, some of 20 the parts being shown in side elevation.

My invention is in the nature of an improvement upon the combined clock and bell patented to me January 21, 1890, No. 419,686, and the general arrangement of the bell-ring- 25 ing mechanism and the clock is the same as in said patent.

B designates a base of any suitable construction provided with a central hub and interiorly-threaded hole to receive the hollow 30 stem 5, Fig. 2, of the standard, which supports the clock-case A. This hollow stem is secured to the lower plate 6 of the frame of the bell-ringing mechanism, said plate being provided with pillars or posts 7, to which the 35 upper plate 8 is secured, said two plates and posts constituting the frame of the bell-ringing mechanism. Mounted in or on this frame is a main shaft, ratchet-wheel, pawl, main-spring, escapement-wheel, and hammer, the

40 same forming a bell-ringing mechanism of ordinary construction, which I consider unnecessary to describe. Projecting upwardly from the hammer of said bell-ringing mechanism, into the lower part of the clock-case, 45 is a holding arm or wire 9, the upper portion of which occupies a position near the axial line of the hollow stem 5, and center of the bell and frame of the bell-ringing mechanism.

Above the upper plate of the bell-ringing 50 mechanism is a supporting-plate 10, the same being secured to said upper plate. On the

hollow stem, between the frame of the bell-ringing mechanism and the base B, there is a gong-shaped bell C, which incloses the bell-ringing mechanism, said bell being in an inverted position—that is, with its open side 55 uppermost.

D designates a cover or cap of any desirable form for covering the upper open side of the bell.

I provide the clock-case with any suitable support or foot—as, for instance, the plate 4 and arms 3. This plate 4 and the cap or cover D are secured to the plate 10 by means of screws 11, which pass through the plate 4 65 and cover D into threaded holes in the plate 10. As the top of the bell and foot or plate under the clock-case in my former patent were provided with a central opening through which the holding-arm 9 projected upwardly, 70 so in like manner the plate 4, cover D, and plate 10 are also provided with a central opening for the same purpose.

The time-piece within the clock-case A is provided with a holding and releasing lever 75 15, having a rearwardly-extended foot 16 in the lower part of the case for engagement with the holding-arm 9, all as in my aforesaid patent. The winding-key 12 of the bell-ring- 80 ing mechanism projects downwardly through the hollow stem 5 at the center of the base B, said mechanism being of the kind known by the term "central winding." The holding and releasing lever 15 will be operated by the time-movement to disengage the holding-arm 85 9 at the predetermined time, as in prior alarms, the manner of so doing forming no part of the present invention further than that the holding-arm 9 is nearly in the position 90 of the axis of the bell.

I claim as my invention—

1. A combined clock and bell, with the bell 95 C mounted underneath the clock and centrally thereto in an inverted position, and the cap D, between the open top of the bell and the clock, with the holding-arm 9 extended upwardly through the central portion of said cap, substantially as described, and for the purpose specified.

2. A combined clock and bell connected together, with the bell between the clock-case and the supporting-case B, and a central-wind-

ing bell-ringing mechanism inclosed within said bell, substantially as described, and for the purpose specified.

3. A combined clock and bell consisting of 5 the base B, the bell C, the frame of the bell-ringing mechanism mounted upon a hollow stem extending through the central portion of said bell and base, the cap D, secured over said frame, and the clock A, mounted upon 10 said cap, substantially as described, and for the purpose specified.

4. A combined clock and bell connected together, the bell being mounted in an inverted position, with the winding-key projecting at

the center of its under side, and a cap or 15 cover over the open top of said bell between said top and the clock, substantially as described, and for the purpose specified.

5. A combined clock and bell consisting of the clock and case A, the base B, and an inverted bell centrally mounted over said base and between said base and case, substantially as described, and for the purpose specified. 20

ALMERON M. LANE.
